UNITED STATES PATENT OFFICE.

BENJAMIN S. ROBERTS, OF THE UNITED STATES ARMY.

IMPROVEMENT IN PROJECTILES FOR RIFLED ORDNANCE.

Specification forming part of Letters Patent No. 37,979, dated March 24, 1863.

To all whom it may concern:

Be it known that I, BENJAMIN S. ROBERTS, of the United States Army, have invented a new and improved mode of constructing shot and shell, which are intended to be thrown from rifled cannon; and I do hereby declare that the following is a full and exact description thereof, which will be more fully understood by reference to the accompanying drawings, in which—

Figure 1 represents the body of the shot or shell. Fig. 2 is a section of the shell when complete. Fig. 3 is a section of the shell along the line xx of Fig. 2. Fig. 4 is a longitudinal section of a cup or band of soft metal which is to fit onto the rear portion of the projectile. Fig. 5 is a modification of the projectile.

My invention consists in a shot or shell made of two principal parts, the front and central portion constituting the chief bulk of the projectile being composed of cast-iron, and the rear portion of the projectile is surrounded by a cup or band of soft metal, which is intended to constitute a part of the projectile and to fly with it. This cup or band may be composed of any metal of the proper degree of hardness and tenacity; but I prefer making it of lead, or some of the compounds of which that metal constitutes one of the ingredients. The "point" or forward end of the projectile may be made in any of the usual shapes. A little forward of the center of gravity of the whole shot (including the cup or band) I construct a shoulder, making the rear portion of the cast-iron part of the shot smaller than the largest diameter of the same, thus leaving a suitable space for the reception of the soft-metal cup or band. This rear portion of the cast-iron part of the shot I call the "spindle." It may be made in the form of a cone, or of the frustum of a cone, or in various other shapes; but, for reasons hereinafter given, I prefer giving it the shape of a paraboloid and of a frustum thereof. Upon this spindle I form tongues or "lands," which are made to fit into grooves cast upon the interior surface of the cup or soft-metal band, in order that the soft metal may have so firm a grip upon the main portion of the projectile that when rotation is given to the former it will be sure to carry the latter with it. The soft-metal cup or band may be cast separately and afterward driven on upon the cast-iron spindle; or the body of

the shot having been first constructed and placed in a proper mold, the soft metal may be cast upon the shot at once. In rear of the shoulder and in front of the cup or band I leave a small ring or space, extending entirely around the projectile; or, instead of a continuous ring, independent recesses of a semicircular or other form may be constructed, as shown in Fig. 1. This ring or these recesses are intended to be filled with a lubricating compound previous to the firing of the projectile. They also leave room for the cup or band to be propelled forward, in order that it may be more readily and uniformly expanded, so as to fill the grooves of the cannon. This cup or band may be shaped as in Fig. 5, entirely closed in the rear; but I prefer leaving it open at the bottom, as shown in Fig. 2, and even if the outer angles at the rear end, ff , are cut off, as shown in Fig. 2 in red lines, the effectiveness of the soft-metal band will not be greatly diminished, while the range of the shell will probably be thereby increased. The projectile, having been thus prepared, is to be inserted into the muzzle of the gun and rammed home in the usual way. The explosion of the powder forces the soft metal forward upon the spindle, causing it to expand, so as entirely to fill the bore of the cannon and prevent windage.

It is a well-known property of the parabola that the abscissas are proportional to the squares of the ordinates. By making the spindle of the form of a paraboloid, therefore, the circles formed by sections of this paraboloid perpendicular to its axis will be in direct proportion to their respective distances from the apex of the paraboloid, inasmuch as these circles are in direct proportion to the squares of their radii—that is to say, they are, in direct proportion to their respective distances from the apex of the paraboloid. In such cases, therefore, this band of soft metal, if driven directly forward, will swell equally at all points of its length, so as to take the same hold of the grooves of the cannon at all those points. This effect may be produced sufficiently for all practical purpose without making the spindle an exact paraboloid. It will be sufficient if it has a curved surface nearly approximating that form, the enormous pressure of the liberated gases being sufficient to overcome any defects in the shape of the spindle in this particular; but I prefer making the convex

surface of the tongues or lands of the spindle of the form of one paraboloid, and the convex surface of the bottom of the grooves on the spindle of another paraboloid having a common apex, in which case the expansion of the soft metal will be exactly equal throughout its entire length.

I make the entire projectile, including the soft metal, of such proportions that the center of gravity will fall in rear of the shoulders *g g*, so that the projectile may have a longer bearing in the gun, and, taken in connection with the shape and proportions of the parts in other respects, will cause it to fly steadily without any danger of "tumbling," and without any serious exhibition of what is termed "nutation" in its flight.

I sometimes form a ring-shaped concavity, *e e*, around the whole circumference of the rear end of the shot in the soft-metal band, by which means a rim will be provided which will be forced into the grooves of the cannon on the same principle as that which gives the Minié ball its distinguishing property.

The shoulders *g g*, instead of being constructed at right angles to the axes of the shot, may be made with an acute angle, having its point forward, by which means the soft-metal band will be stayed and supported by these acute-angled shoulders.

I am aware that projectiles have been constructed having their main body composed of cast-iron with a band of soft metal attached to the rear end of such body, and so contrived that the expansive force of the gases resulting from the explosion of the powder, acting from within or underneath this soft metal, should force it outward into the grooves of the cannon to communicate a rotary motion to such projectile. This plan is objectionable principally for the reason that it does not hold the projectile firmly in the axis of the cannon, by which means a wobbling motion is communicated to it.

I am also aware that projectiles have been constructed having a main body of cast-iron surrounded by a band of soft metal or its equivalent, which was followed up by a ring or cup of cast-iron, by means of which the soft metal would, upon the discharge of the cannon, be pressed between two shoulders of iron, and thus forced out into the grooves of the cannon. This arrangement is liable to the objection that it is composed of too many parts, and the ring or cup which is made to follow up the band of soft metal is liable to be broken or to fly from the base of the projectile.

I am likewise aware that a band or sabot of soft metal has been contrived by William E. Woodbridge, embracing the rear end of a cast-iron shot, and extending forward so as measurably to embrace the center of gravity of the projectile; but as its exterior surface is left smooth, without shoulder or grooves, the soft sabot will have nothing against which to abut, in order to be forced into the grooves of the

gun; and, even if that objection did not exist, the absence of grooves or their equivalent would leave the sabot without a sufficient hold upon the shot to insure its being rotated by the rotation of the sabot.

Finally, I am aware that, in 1861, John A. Dahlgren obtained a patent for a shot composed of a cast-iron body, having its rear end inclosed by a soft-metal cup, having also a shoulder to abut against, and longitudinal tongues fitted to grooves in the soft-metal cup, in order to insure rotation in the hard-metal body whenever the soft-metal cup was made to rotate; but this soft metal of Dahlgren was only intended to embrace the base of the body of the shot. He had never contemplated such a contrivance as should prevent the hard cast-iron portion of the projectile from being brought into violent collision with the internal surface of the bore of the gun. On the contrary, he constructed longitudinal ribs upon the exterior surface of his shot to diminish the friction by diminishing the extent of the surface that should actually be brought in contact with the surface of the bore of the gun, whereas by my arrangement the axis of the projectile is held steadily in the axis of the gun, and the hard-metal body of that projectile is kept entirely out of contact with the metal of the gun, by which means cannon made of brass or other soft metal can be safely used, which can never be the case with the Dahlgren shot.

What, therefore, I claim as new, and desire to secure by Letters Patent, is—

1. In a projectile for rifled ordnance composed of a body of cast-iron and a cup or band of soft metal, and having upon its body a shoulder running transversely around the same, and a spindle furnished with longitudinal tongues and grooves, constructing the projectile of such proportions that the soft metal shall so embrace the center of gravity of the entire projectile as to furnish a bearing for the same while passing through the cannon, substantially in the manner and for the purpose above described.

2. In a projectile constructed as described in the preceding claim, forming the surface of the spindle in the shape of a paraboloid, or such an approximation thereto that the soft metal may, by the force of the explosion, be crowded uniformly outward on all sides and at all parts of its length, whereby the axis of the projectile may be placed and held firmly in the axis of the cannon while passing through the same, thereby securing a steady motion of rotation to the shot throughout its flight, substantially as and for the purpose above described.

Witness my hand and seal, in the matter of my application for a patent for improved shot and shell, this 22d day of December, A. D. 1862.
